UNITED STATES PATENT OFFICE.

FRANZ KRATZ AND ROBERT WAGNER, OF STUTTGART, GERMANY, ASSIGNEES TO THE FIRM OF ROBERT BOSCH, OF STUTTGART, GERMANY.

TERMINAL CONNECTOR FOR CONCENTRIC-CONDUCTOR CABLES.

1,079,130.

Specification of Letters Patent.

Patented Nov. 18, 1913.

Application filed May 1, 1913. Serial No. 764,745.

To all whom it may concern:

Be it known that we, FRANZ KRATZ, a subject of the Emperor of Germany, residing at and whose post-office address is No. 5 59 Schlossstrasse, Stuttgart, Germany, and ROBERT WAGNER, a subject of the Emperor of Germany, residing at and whose post-office address is No. 41 Seestrasse, Stuttgart, Germany, have invented certain new and 10 useful Improvements in Terminal Connectors for Concentric-Conductor Cables; and we do hereby declare the following to be a full, clear, and exact description of the invention, such as will enable others skilled 15 in the art to which it appertains to make and use the same.

The present invention relates to terminal connectors for concentric conductor cables, and particularly to connectors of this kind 20 for reliably connecting the two electrical conductors of the cable to the two terminals of a translating device, wherein there are two electrodes insulated from each other for connection to the two conductors of the 25 cable, and two abutments insulated from each other for connection to the terminals of the translating device, a pressure applying device being employed to force the individual electrodes into intimate electrical 30 connection with the abutments and with the conductors to thereby establish reliable connection between the two conductors of the cable and the two terminals of the translating device.

35 Although our invention may be embodied in a variety of constructions, yet we prefer to construct the electrodes in the form of split sleeves having conical bearing surfaces fitting into a conical seat in one abutment 40 and into a conical seat of a tubular socket which is screwed into the other abutment, the conductor cable passing through the socket and the individual conductors being gripped by the two split sleeves.

45 In the accompanying drawings, illustrating several modifications within our invention of the electrodes of the cable connectors, and several modifications within our invention of the abutments, Figure 1 represents 50 a section of one form of connector, showing the electrodes in elevation; Fig. 2 represents a similar section of another form of connector; Fig. 3 represents a central section of the electrodes of Fig. 2; Fig. 4 represents

a central section of the preferred form of connector; Figs. 5 and 6 represent central sections of modified forms of electrodes; Figs. 7, 9, 11 and 13 represent sectional views, partly broken away, of an incandescent head light, as an example, in which various forms of abutments are carried by the reflector thereof; and Figs. 8, 10, 12 and 14 represent sectional views at right angles to the preceding figures.

In all the drawings *e* and *d* are the electrodes of the terminal connectors, *i* is the tubular socket, *k* and *l* are the two abutments, and the conductor cable comprises the inner insulated conductor *r* and the outer concentric conductor *s* which is shown as the 60 outside armor or sheath of the cable.

In Fig. 1, the electrode *d* of metal is a slotted shell with an internal bore just large enough to receive the outer sheath *s* of the cable and with a conical end bearing surface 75 as shown. The electrode *e* of metal is insulated from the electrode *d* by the insulation *f*, and it has a flat top and a central bore suitable for passage therethrough of the inner conductor *r* as shown.

80 Fig. 2 is similar to Fig. 1, excepting that the top of the electrode *e* is conical.

As shown in Fig. 3, the insulating ring *f*₂ and the insulating tube *f*₁ insulate the electrodes *d* and *e*, while the metal sleeve *n* 85 is forced into contact with the electrode *e* by turning over its top edge.

In both Figs. 1 and 2, the strands of the conductor *r* are bent over the top of the electrode *e* and are pressed into intimate 90 electrical contact with the abutment *k* by screwing the socket *i* into the abutment *l* until both electrodes are tightly seated and the electrode *d* squeezed tightly around the outer sheath *r*. The abutments *k* and *l* are 95 insulated from each other by the insulating piece *t*, so that the two conductors *r* and *s* are thereby electrically connected to the respective abutments *k* and *l*, which may be electrically connected in any suitable way to 100 the two terminals of a translating device.

The construction shown in Fig. 4 is similar to that previously described, excepting that the electrode *e* is also slotted so as to tightly grip a solid conductor *r*. Furthermore, the electrode *d* has an upper cupped extension insulated from the electrode *e* by the insulating tube *f*₄ and the insulating

ring f_3 . Also, the abutment k is held in place by insulated screws from an upper extension of the abutment l .

5 In Fig. 5, the parts f_1 , f_2 and n are replaced by a single insulating piece f .

10 In Fig. 6, the insulating tube f_1 is separate from the insulating ring f_2 , the advantage being that the ring f_2 may then be made of stronger insulating material so that a greater pressure may be safely applied to the electrode.

15 Figs. 7 to 14 show the terminal connectors applied to a head light as an example, the incandescent lamp a having one of its terminals electrically connected by the leaf spring c to the abutment k and the other terminal electrically connected to the abutment l through the lamp frame. The two abutments are fixed to the lamp reflector b and are insulated from each other by the insulating pieces t . In Figs. 7 and 8, the abutment k is circular in cross section and is held in place by clamping pieces fastened together by insulated screws as shown. The 20 construction shown in Figs. 9 and 10 differ from that of Figs. 7 and 8 in that the abutment k is held in place in a bored recess in the abutment l . In Figs. 11 and 12, the abutment k has flat sides and is held in place 25 by screws v insulated from the abutment k by insulating bushings w . Figs. 13 and 14 show the preferred form of electrodes associated with the preferred arrangement of the abutments in a reflector lamp, in which 30 the abutment k is hung from an upper extension of the abutment l by the screws v and is insulated therefrom by the insulating pieces t and the insulating bushings w for the screws.

35 40 Having thus described our invention, what we claim is:—

1. The combination with a concentric conductor cable, of a terminal connector therefor comprising two conducting electrodes 45 insulated from each other for electrical connection to two insulated conductors of the cable, two abutments insulated from each other, and a conducting pressure-applying device coöperative with one of said abutments and with one of said electrodes to force the other electrode into intimate contact with the other abutment and thereby 50 electrically connect the two conductors of the cable with the respective abutments, said pressure-applying device having a central 55 opening for the passage of the cable therethrough; substantially as described.

2. The combination with a concentric conductor cable, of a terminal connector therefor comprising a conducting electrode having a split conical portion for electrical connection to the inner insulated conductor of the cable, a conducting electrode insulated from the other electrode and having a split 60 conical portion for electrical connection to the outer conductor of the cable, an abutment having a conical seat for the conical

portion of the first mentioned electrode, an abutment insulated from the other abutment, and a conducting pressure-applying device coöperating with the second mentioned abutment and having a seat coöperating 70 with the conical portion of the second mentioned electrode to force the electrodes into intimate contact with the conductors and with the seats to thereby electrically connect the two conductors with the respective abutments; substantially as described.

3. The combination with a concentric conductor cable, of a terminal connector therefor comprising a conducting electrode for electrical connection to the inner insulated 80 conductor of the cable, a conducting electrode insulated from the other electrode and having a split conical portion for electrical connection to the outer conductor of the cable, an abutment having a seat for the first 85 mentioned electrode, an abutment insulated from the other abutment, and a conducting pressure-applying device coöperating with the second mentioned abutment and having a seat coöperating with the conical portion 90 of the second mentioned electrode to force the electrodes into intimate contact with the conductors and with the seats to thereby electrically connect the two conductors with the respective abutments; substantially as 95 described.

4. The combination with a concentric conductor cable, of a terminal connector therefor comprising two conducting electrodes insulated from each other for electrical connection to two insulated conductors of the cable, two abutments insulated from each other, and a conducting pressure-applying device coöperative with one of said abutments and with one of said electrodes to 105 force the other electrode into intimate contact with the other abutment and thereby electrically connect the two conductors of the cable with the respective abutments, said pressure-applying device having a central 110 opening for the passage of the cable therethrough; substantially as described.

5. The combination with a concentric conductor cable, of a terminal connector therefor comprising two conducting electrodes 115 adapted to be electrically connected to the insulated conductors of the cable, two abutments insulated from each other, and a conducting pressure-applying device coöperative with one of said abutments and with one of said electrodes to force the other electrode into intimate contact with the other abutment and thereby electrically connect the two conductors with the respective abutments, said electrodes being insulated from each other by an insulating member having an opening for the passage 125 therethrough of one conductor of the cable; substantially as described.

6. The combination with a concentric con- 130

ductor cable, of a terminal connector therefor comprising two conducting electrodes insulated from each other for electrical connection to two conductors of the cable, two abutments insulated from each other, and a conducting pressure-applying device coöperative with one of said abutments and with one of said electrodes to force the other electrode into intimate contact with the 10 other abutment and thereby electrically connect the two conductors with the respective abutments, one of said electrodes having a cupped extension surrounding a part of the other electrode; substantially as described.

15 7. The combination with an electric head light having a reflector, of a terminal connector for connecting the conductors of a concentric cable to the terminals of a lamp comprising two conducting electrodes insulated from each other for electrical connection to the two 20 terminals of the lamp, and a conducting pressure-applying device coöperative with one of said abutments and with one of said electrodes to force the electrodes into intimate contact with the conductors and 25 into electrical connection with the abutments to thereby electrically connect the conductors with the respective terminals of the lamp; substantially as described.

30 8. The combination with an electric head light having a reflector, of a terminal connector for connecting the conductors of a concentric cable to the terminals of the lamp comprising two electrodes insulated from each other for electrical connection to 35 two insulated conductors of the cable, a conducting abutment mounted on the reflector for electrical connection to one terminal of the lamp, a second conducting abutment carried by the other abutment and being in-

sulated therefrom for electrical connection 45 to the other terminal of the lamp, and a conducting pressure-applying device coöperating with one of said abutments and with one of said electrodes to force the electrodes into intimate contact with the conductors and into electrical connection with the abutments to thereby electrically connect the conductors with the respective terminals of the lamp; substantially as described.

50 9. The combination with an electric head light having a reflector, of a terminal connector for connecting the conductors of a concentric cable to the terminals of the lamp comprising a conducting electrode having a 55 split conical portion for electrical connection to one conductor of the cable, a conducting electrode insulated from the first and having a split conical portion for connection to the other conductor of the cable, 60 a conducting abutment mounted on the reflector for electrical connection to one terminal of the lamp, a second conducting abutment insulated from the first abutment for electrical connection to the other terminal of the lamp and having a seat for the conical end of one electrode, and a tubular socket having a seat for the conical end of the other electrode and being adapted to be screwed into the first mentioned abutment 65 to force the conical portions of the electrodes into intimate contact with the conductors and with their seats to thereby electrically connect the two conductors of the 70 cable with the respective terminals of the lamp; substantially as described.

75 In testimony whereof we affix our signatures, in presence of two witnesses.
